UNITED STATES PATENT OFFICE

GEORGE FREDERICK CLARK, OF WEST DRAYTON, ENGLAND, ASSIGNOR, BY MESNE ASSIGNMENTS, TO RADIO CORPORATION OF AMERICA, OF NEW YORK, N. Y., A CORPORATION OF DELAWARE

AUTOMATIC STOPPING DEVICE FOR TALKING MACHINES

Application filed April 27, 1929, Serial No. 358,653, and in Great Britain June 5, 1928.

This invention relates to improvements in automatic stopping devices for talking machines and in particular to stopping devices of the kind which are operable to stop the machine when the direction of movement of the sound arm is reversed as by the engagement of the stylus in an eccentric groove provided at the centre of the record. The invention is particularly adapted for use in conjunction with means operable to stop the machine by friction upon the turntable spindle or the central boss of the turntable.

The stopping means according to the invention comprises a movable member adapted to be moved in conjunction with the sound arm, a second movable member in frictional engagement with the first movable member, said second movable member being adapted to remain stationary during movement of the sound arm and the first movable member in one direction and to be moved to operate a stop member when the sound arm and first movable member are moved in the other direction.

25 The stop member comprises a pivotally mounted lever which is movable first in one direction and then in the other direction during movement of the sound arm in one direction only.

30 In the preferred construction the stopping member in the stopping position engages with a radial extension on a sleeve in frictional engagement with the central boss beneath the turntable whereby movement of the sleeve is prevented and the turntable is brought to a standstill by friction.

The invention is illustrated by way of example in the accompanying drawings in which,

40 Fig. 1 is a plan view with the parts in the stopping position.

Fig. 2 is a plan view with the parts in the "off" position.

45 Fig. 3 is an elevation of the braking mechanism detached from the machine.

Figs. 4 and 5 are detail views of the parts of the braking mechanism carried on the turntable spindle.

50 Referring to the drawings, 1 is the usual turntable spindle driven by the motor of the

machine and carrying the usual turntable 2 indicated in dotted lines in Fig. 1. The sound arm 3 is pivoted at 4 on the machine and carries the usual reproducer 5. Upon the vertical portion of the pivoted sound arm 3 is fixed a lever 6 carrying a pin 7 which co-operates with a lever 8 pivoted at 9 on a base plate 10. The pin 7 operates to move lever 8 through a pair of spring connected jaws 11, 12, by reason of the fact that jaw 12 is integral with lever 8.

Upon the same pivot 9 is mounted a lever 13 which is held in frictional engagement with lever 8 through a spring washer 14 so that it moves therewith when free to do so.

65 The outer end of the lever 13 is bifurcated as shown at 15 and engages with a pin 16 upstanding from a stop lever 17 pivoted at 18 on the base plate, and this stop lever 17 is capable of movement about its pivot 18 between extreme positions where it contacts with one or other of two stops 19, 20 on the base plate.

70 The end of stop lever 17 is formed with an extension 21, the edge of which forms a cam surface for engagement by a pin 22 in the extremity of lever 8.

75 The central boss 23 on the underside of the turntable 2 is in the form of a cup apertured at the bottom as shown at 24 for the passage of the turntable spindle 1 and provided with an outwardly directed flange 25 whereby connection to the turntable 2 may be effected as by spot welding for example.

80 A recess 26 is formed at the lower end of the boss which engages a pin, not shown, on the turntable spindle in usual manner to ensure rotation of the turntable with the spindle.

85 In the walls of the cup forming boss 23 are provided a number, three for example, of spaced apertures in which are housed pads 27 of fibre or the like and these pads are held in position by means of a spring ring 28 within the boss and engaging in shallow recesses in the inner surfaces of the pads 90 27. The spring ring serves also to urge the pads radially outwards into frictional contact with the inner surface of a sleeve 29 which surrounds the boss 23. The sleeve may be recessed on its inner surface as shown at 100

30 so that it is retained in position on the boss by engagement of the pads 27 in the recess.

From the outer surface of the sleeve 29 extend one or a number of lugs 31, and these 5 lugs are adapted to cooperate with the stop member 17 referred to above.

The operation is as follows:

Assuming the stylus of the reproducer 5 to be engaged with a record being played.

10 In these conditions the lever 8 is being rocked in a counterclockwise direction about its pivot 9 and lever 13 tends to rotate in the same direction by virtue of its frictional connection through friction washer 14 with lever 8. The lever 13 however, is connected through pin 16 with stop lever 17 and holds said stop lever in contact with stop 20 by virtue of its tendency to move with the lever 8. In consequence lever 13 is held against movement 20 and slip takes place between levers 8 and 13.

When the end of the record is reached and a reversal of the direction of movement of the sound arm 3 is effected, as by the stylus entering an eccentric groove 32, the lever 8 25 is moved in a clockwise direction about its pivot 9 and lever 13 moves in the same direction by virtue of its frictional connection with lever 8 through washer 14 and the stop lever 17 is moved from the position shown in 30 Fig. 2 to the position shown in Fig. 1 where its end engages one of the projecting lugs 31 on sleeve 29. The sleeve 29 is brought at once to a standstill and the rotation of the turntable ceases through the frictional 35 engagement between the pads 27 and the sleeve 29.

Subsequent movement of the sound arm 3 outwards causes lever 8 to rock further in a clockwise direction and pin 22 on lever 8 en- 40 gages the cam surface on extension 21 of lever 17 as shown in Fig. 2 whereby the lever 17 is returned to the non-stopping position against stop 20 due to slippage again taking place between lever 8 and lever 13, as the lat- 45 ter moves into the position which it occupies during playing.

I claim:

1. Automatic stopping means for a talking machine comprising a movable member 50 adapted to be moved in conjunction with the sound arm, a stopping member movable between stopping and non-stopping positions, a second movable member in frictional engagement with said first movable member and connected to said stopping member to move the latter, means for holding said second member stationary during movement of the sound arm and first member in one direction, and means operative upon 60 movement of said sound arm in the other direction to move said stopping member into non-stopping position independently of said second member.

2. Automatic stopping means for a talk- 65 ing machine comprising a movable member

adapted to be moved in conjunction with the sound arm, a stopping member movable between stopping and non-stopping positions, an operating member having frictional engagement with said movable member and pivotal engagement with said stopping member, and means holding said operating member stationary with said stopping member in non-stopping position during movement of said sound arm in one direction.

3. Automatic stopping means for a talking machine comprising a movable member adapted to be moved in conjunction with the sound arm, a stopping member movable between stopping and non-stopping positions, an operating member having frictional engagement with said movable member and pivotal engagement with said stopping member, means holding said operating member stationary with said stopping member in non-stopping position during movement of said sound arm in one direction, said operating member being movable with said movable member when the sound arm moves in the opposite direction to move said stopping member to stopping position, and means on said movable member operable on continued movement of said sound arm in said opposite direction to move said operating member and stopping member to non-stopping position.

4. Automatic stopping means for a talking machine comprising a pivoted stop member, a member movable in conjunction with the sound arm, and a second member having frictional engagement with said first member, said second member being adapted to move said stop member in one direction and said first member being adapted to move said stop member in the opposite direction as said sound arm is moved in one direction only.

5. Automatic stopping means for a talking machine comprising a pivoted stop member, a member movable in conjunction with the sound arm, and a second member having frictional engagement with said first member, said second member being adapted to move said stop member to stopping position as said sound arm moves outwardly and said first member being adapted to move said stop member to non-stopping position upon further movement of said sound arm outwardly.

6. Automatic stopping means for a talking machine comprising a pivoted stop member, a member movable in conjunction with the sound arm, and a second member having frictional engagement with said first member and pivotal engagement with said stop member, said second member being adapted to move said stop member to stopping position as said sound arm moves outwardly and said stop member having a cam surface adapted to be engaged by said first member on continued movement of said sound arm outwardly to move said stopping member to non-stopping position.

7. In apparatus of the class described, the combination of a turntable having a hollow boss, a sleeve surrounding said boss, means carried by said boss and frictionally engaging said sleeve, a radial projection on said sleeve, a stop member movable into and out of the path of movement of said projection, and means movable in conjunction with the sound arm for moving said stop member into and out of the path of movement of said projection.

8. In a talking machine, the combination of a turntable having a hollow boss and an aperture in the wall of said boss, a sleeve surrounding said boss, a friction element in said aperture, means yieldingly urging said element into frictional engagement with said sleeve, a radial projection on said sleeve, a pivoted stop member movable into and out of the path of movement of said projection, and means movable in conjunction with the sound arm for operating said stop member.

9. In a phonograph, the combination with a turntable of an annular brake sleeve having operative frictional engagement with said turntable and normally rotatable therewith, a stop mechanism including a brake engaging member and a pivoted lever operable by and upon a reverse movement of the tone arm to move said member into and out of the path of said brake sleeve.

10. In a phonograph including a pivotally supported tone arm and a turntable, a brake having operative frictional engagement with said turntable and normally rotatable therewith, means actuated by said tone arm upon a limited reverse movement thereof at a point adjacent the center of said turntable in its normal direction of movement for causing the application of said brake, and means controlled by said tone arm upon a complete movement of said tone arm in said reverse direction for releasing said brake.

11. In a phonograph having a sound reproducing instrumentality, the combination with a record-support including a boss thereon and a driving spindle for said support of automatic stopping means comprising a sleeve adapted to be driven by said spindle and having operative frictional engagement with said boss, radial projections carried by said sleeve, a stop member movable into and out of the path of movement of said projections, means movable in conjunction with said instrumentality for moving said stop member into and out of the path of movement of said projections, and means connecting said stop member and said last named means whereby motion may be transmitted to said stop member by said instrumentality.

12. In a phonograph including a pivotally supported tone arm and a turntable having a boss thereon, a brake sleeve having operative frictional engagement with said boss and normally rotatable therewith, means actuated

by said tone arm upon a limited reverse movement thereof adjacent the center of said turntable in its normal direction of movement to interrupt the rotation of said sleeve, and means controlled by said tone arm upon a complete movement thereof in said reverse direction for releasing said sleeve.

13. In a talking machine having a sound arm, the combination with a turntable including a boss thereon, of automatic stopping means comprising a projection frictionally engaging and being rotatable with said boss, a pivoted stop member movable into the path of movement of said projection, means movable in conjunction with the sound arm for moving said stop member into and out of the path of movement of said projection, and means connecting said stop member and said last named means whereby motion may be transmitted to said stop member by said sound arm.

14. In a phonograph including a sound reproducing instrumentality, the combination with a record support having a boss thereon, of automatic stopping means comprising a sleeve having operative frictional engagement with said boss, radial projections on said sleeve, a stop member movable into and out of the path of movement of said projections, means movable in conjunction with said instrumentality for moving said stop member into and out of the path of movement of said projections, and means connecting said stop member and said last named means whereby motion may be transmitted to said stop member by said instrumentality.

15. In a phonograph, a rotatable record-support, a braking device carried by and normally rotatable with said support, a pivotally supported sound reproducing instrumentality, means actuated by said instrumentality upon a limited reverse movement thereof adjacent the center of said record support for engaging said braking device to impede the rotation of the record-support and means actuated by said instrumentality upon continued movement thereof in the reverse direction for disengaging said braking device.

In testimony whereof I have signed my name to this specification.

GEORGE FREDERICK CLARK.
